UNITED STATES PATENT OFFICE.

BERNHARD WIESENGRUND AND WILLIAM FREDERICK ROBERTS, OF WEST DRAYTON,
ENGLAND.

TOOTHED GEARING.

1,019,001.

Specification of Letters Patent. Patented Feb. 27, 1912.

Application filed July 20, 1911. Serial No. 639,551.

To all whom it may concern:

Be it known that we, BERNHARD WIESEN-
GRUND, a subject of the German Emperor,
and WILLIAM FREDERICK ROBERTS, a subject
5 of His Majesty the King of Great Britain,
both residents of West Drayton, in the
county of Middlesex, England, have in-
vented a new and useful Improvement in
Toothed Gearing, of which the following is
10 a specification.

In high speed driving gearing for large
powers, particularly in double or multiple
helical spur gearing of great face width, it
is of the utmost importance to insure as far
15 as possible an even distribution of load over
the whole face width, in order to avoid un-
even wear of the teeth, incalculable differ-
ences in stresses in different portions of the
teeth and vibration which results from un-
20 even load distribution. The most favorable
distribution of load over the whole avail-
able face width should be obtained without
sacrificing perfect rigidity of the supports
of the driving pinions and driven wheels in
25 speed reducing gears, or driving wheels and
driven pinions in speed increasing gears.
It is obvious that with very small diameter
of driving or driven pinions which are
necessary to keep the surface speed within
30 admissible limits it will be impossible to ob-
tain a satisfactorily even distribution of the
load when applying or delivering the power
at one end of a very wide pinion on account
35 of the distortion (twisting) of such pinion
due to torsional stresses. In order to obtain
the desired even distribution of load we
make therefore each pinion in two parts,
each part forming a hollow sleeve and pro-
40 vided with a coupling flange at one end.
Immediately adjoining the coupling flanges
journals are formed on the sleeves and the
ends of the sleeves which are not provided
with coupling flanges are also formed as
45 journals. Between the two journals of each
sleeve the teeth are cut, right hand helical
on one, left hand helical on the other, or
double or multiple helical on either. If
double or multiple helical teeth are cut on
50 both sleeves each can be regarded as a com-
plete pinion, the two treated in the same
way as the two parts of one. The coupling
flanges of the two sleeves form their inner
ends, and are connected by a third coupling
55 member connected to one driving shaft pass-
ing through one of the sleeves, or to two

driving shafts each passing through one of
the sleeves, the latter arrangement being
necessary where two sources of power have
to work on one pinion or two pinions with
common axis. The coupling flanges on the 60
sleeves can also be bolted together directly,
and the driving shaft connection to the sleeve
effected by means of keys or other suitable
means. The coupling may be of the solid
65 flanged type with parallel or taper bolts or
of the claw type to admit of slight longitudi-
nal movement and expansion, or any other
suitable type of coupling may be chosen.
Where the connection of the sleeves to the
70 driving shaft or shafts is effected by keys,
a coupling may be altogether dispensed
with.

In the accompanying drawings: Figure 1
is a sectional view showing two part sleeve
pinions together with one method of cou- 75
pling the shafts of the small pinions. Fig.
1^A is a similar view showing the shafts of the
pinions bolted together by suitable flanges
carried by the shafts. Figs. 2, 3 and 4 show
what are practically similar views with dif- 80
ferent also known forms of teeth and cou-
plings and Fig. 5 shows diagrammatically
one application of the invention in a case in
which the power from or to four separate
85 points is transmitted to or from a single
shaft.

In Fig. 1 the four journals e' e^2 e^3 and e^4
are shown as supported by the bearings f' f'
and f^2 the bearing f being preferably a sin- 90
gle one provided with a central space to ac-
commodate the coupling. The two parts
 a' a^2 indicate the sleeve pinion which may
also be regarded as separate pinions gear-
ing into gear wheels g' g^2 shown as two 95
parts of one wheel or two wheels mounted on
a common sleeve h or they may be mounted
directly on the driving or driven shaft h as
the case may be and as shown in Fig. 1^A. As
shown in Fig. 1 c is the driving shaft or in 100
the case of two sources of power applied in
the same axial line c and c' both act as driv-
ing shafts coupled by coupling members b'
 b^2 and d to the sleeve pinions a' a^2 . In Fig.
1^A practically the same construction is shown 105
except that the gears g' g^2 are secured di-
rectly to shaft h while in Figs. 2 and 3 the
shafts c are shown as connected to the sleeves
by means of keys while in Fig. 4 a claw cou-
pling is indicated while Fig. 5 shows a form 110
of coupling similar to that in Fig. 1.

The various forms of gears and couplings indicated being well known need not be further described.

It will be seen that with all the arrangements described the driving force is always applied from the center or between the gear or pair of gears used, so that any torsion affects equally the portions of the gear or the two gears which are situated symmetrically to the connection of the driving shaft or shafts with the sleeves. In the case of the use of two sources of power in one axis at opposite ends of the gear or gears, the arrangement has the further advantage, that however different the amount of energy supplied by one and the other, the total energy will be evenly distributed over the gear or gears from the central point in which the connection of the driving shafts with the gear or gears is effected.

The description given, heretofore refers equally to speed increasing gears, the shaft or shafts through which the power is delivered to the driven machine or machines taking the place of the driving shaft or shafts, as according to this invention one or more power shafts whether receiving power as for example from a turbine or whether transmitting it, as for example to a dynamo receive or transmit the power in lines parallel and co-axial with rigidly supported split or pairs of gear wheels which are not relatively movable otherwise than parallel to their axis the power being imparted to or transmitted from such gears through a connection made between the shaft and gears at a point between said gears.

In all drawings we have shown two pinions engaging with one wheel on opposite sides of the wheel in one plane, but in some cases even more pinions may be used suitably arranged around the circumference of the wheel.

What we claim is:—

1. In toothed gearing, rigidly supported pairs of gear wheels which are not relatively

movable except in lines parallel to their axis, one or more power shafts receiving power from a point or points outside the gear wheels but in direct line therewith and transmitting such power to a point intermediate of the gear wheels and means for transmitting such power from said point to the gear wheels.

2. In toothed gearing, rigidly supported pairs of gear wheels which are not relatively movable except in lines parallel to their axis, means for transmitting power from said gear wheels to a point between them, and means for transmitting the power from said point to a point or points outside said gear wheels but in direct lines therewith.

3. In toothed gearing, rigidly supported pairs of gear wheels which are not relatively movable except in lines parallel to their axis, one or more power shafts receiving power from a point or points outside the gear wheels but in direct lines therewith and transmitting such power to a point or points between the gear wheels and means for transmitting such power from said point to the gear wheels and a single shaft driven therefrom.

4. In toothed gearing, rigidly supported pairs of gear wheels which are not relatively movable except in lines parallel to their axis, a single driving shaft, means for transmitting power to said gears and means for transmitting said power from the gear wheels to a point or points between said gear wheels and from said point or points to a point or points outside the gear wheels but in direct line therewith.

In testimony whereof we have hereunto set our hands in the presence of two subscribing witnesses.

BERNHARD WIESENKRUND.
WILLIAM FREDERICK ROBERTS.
